UNITED STATES PATENT OFFICE.

ERNEST H. SCHMIDT, OF CLEVELAND, OHIO, ASSIGNOR TO THE NATIONAL MALLEABLE CASTINGS COMPANY, OF CLEVELAND, OHIO, A CORPORATION OF OHIO.

RADIAL-DRAFT GEAR.

1,090,656.

Specification of Letters Patent.

Patented Mar. 17, 1914.

Application filed January 3, 1913. Serial No. 739,953.

To all whom it may concern:

Be it known that I, ERNEST H. SCHMIDT, a citizen of the United States, residing at Cleveland, Cuyahoga county, Ohio, have 5 invented new and useful Improvements in Radial-Draft Gear, of which the following is a specification, reference being had to the accompanying drawings, in which—

Figure 1 is an elevation of a draft member showing the application of my invention thereto; Fig. 2 is a partial bottom plan thereof; Fig. 3 is a section on lines III—III of Fig. 1; Fig. 4 is a section on lines IV—IV of Fig. 1; and Fig. 5 is a detail thereof.

15 My invention relates to radial draft gear by which the coupler is adapted to be guided to the center of the track, and is designed to provide mechanism whereby the draft member can be disengaged from the guiding connections to permit coupling on a curve with 20 a coupler which is secured to a car in the usual manner. To this end I provide an engagement between the draft member and the guiding connections which can be readily released so that with the car on a curve, 25 the coupler may be swung radially by hand about its pivot into position to couple with an ordinary coupler on the opposing car, which coupler will normally lie at one side 30 of the center of the track and out of alignment therewith. I also provide means for reengagement of the draft member and the guiding connections when the cars have been coupled and have proceeded on their way.

35 Referring to the drawings, 2 is the draft member which is adapted to be pivoted to the car in the manner customary with radial draft gears (not shown), and 3 indicates the guiding connection which is carried by 40 the truck (not shown). Bolted to the under side of the draft rigging casing 4 is a bracket 5, which is T-shaped in cross-section. The clutch 6 which is pivotally suspended from the bracket 5 has a slot 7, the 45 walls of which normally engage the sides of the forward portion of the guiding arm 3 and outer sides 8 of which are inclined outwardly and upwardly. The clutch 6 is pivoted by the lever 9, the bolt portion 10 of 50 which passes through registering apertures in the bosses 11 11', or bifurcated portion, of the clutch 6 and in the web 12 of the bracket 5. The bracket 5 is provided with semi-circular recesses 13 in its rear side 55 which provide a rotative bearing for the

bosses 11 11'. The bolt portion 10 of the lever 9 has a squared part 14 which enters a correspondingly squared recess 15 in the boss 11 of the clutch 6, so as to provide an engagement which will cause the clutch 6 to be rotated when the lever 9 is actuated. The end 16 of the lever 9 is suitably threaded for reception of a nut, or other securing device, which locks together the lever 9, the clutch 6 and the bracket 5, and the other end 65 of the lever is preferably formed with an eye 17 in which a rod 18 or other actuating device may be attached. The forward end of the rod 18 is carried by the coupler support 20 and terminates in the handle 21. 70

The operation of my device is as follows: When it is desired to release the engagement between the clutch 6 and the guiding arm 3, the handle 21 is pulled forwardly which causes the lever 9 to rotate and with it the 75 clutch 6, the lower end of which moves rearwardly and upwardly into the position shown in dotted lines in Fig. 1, so as to completely disengage the clutch and the guiding arm thus permitting a free pivotal 80 movement of the draft member. The coupler and the draft member may then be swung by hand to the left or right as desired in order to couple with a coupler mounted in the ordinary manner on the car. 85 As soon as the operator releases the operating handle 21, the clutch will drop by gravity into normal position. When the car is again in motion the draft member will be eventually swung back to normal position 90 over the center of the track, and in so doing either one side or the other of the guiding arm 3 will engage one of the inclined outer sides 8 of the clutch 6, and will automatically lift the clutch until the arm passes directly beneath the slot, whereupon the clutch 95 will drop by gravity into normal position, and the sides of the slot will reengage the sides of the arm.

It is obvious that many changes may be 100 made in the construction which I have shown and described herein.

What I claim is:

1. In a radial draft gear, a draft member pivotally mounted on a car to swing in a 105 horizontal plane, a guiding connection mounted on the car truck, and a clutch intermediate the draft member and the guiding connection, and adapted to form an interengagement therebetween, said clutch be- 110

ing mounted to move in and out of the path of the guiding connection, and having means coöperating with the guiding connection to permit said connection to lift the clutch to cause it to drop into interengaging position.

2. In radial draft gear, a draft member pivotally attached to a car, a guiding connection attached to the truck, a member intermediate the draft member and the guiding connection, comprising interengaging means therebetween, the said intermediate member lying normally in the horizontal plane of the guiding connection and being arranged to be thrown out of action at will to permit the draft member to be abnormally deflected; the said intermediate member being adapted to be raised by the guiding connection on its return to normal position and to fall into interengagement therewith.

3. In radial draft gear, a draft member pivotally attached to a car, a guiding connection attached to the truck, a member intermediate the draft member, and the guiding connection, comprising a normal connection therebetween and arranged to be thrown out of action at will, outwardly inclined faces on the intermediate member with which the guiding connection is adapted to coat when the draft member is returned into alignment with the guiding connection to raise the intermediate member into position to drop again into interengagement with the guiding connection.

ERNEST H. SCHMIDT.
